UNITED STATES PATENT OFFICE.

RICHARD BERNHARD, OF MILWAUKEE, WISCONSIN, ASSIGNOR TO POWER AND MINING MACHINERY COMPANY, OF CUDAHY, WISCONSIN.

CRUSHING-ROLLS.

956,878.

Specification of Letters Patent.

Patented May 3, 1910.

Application filed December 12, 1907. Serial No. 406,229.

To all whom it may concern:

Be it known that I, RICHARD BERNHARD, citizen of the United States, residing at Milwaukee, in the county of Milwaukee and State of Wisconsin, have invented certain new and useful Improvements in Crushing-Rolls, of which the following is a specification, reference being had therein to the accompanying drawing.

10 This invention relates to improvements in crushing rolls of the class used for grinding rock, reducing ores, and materials of that class.

15 It relates more particularly to improvements by means of which one or both of the rolls of a pair can be moved longitudinally from one position to another and can be firmly fixed in position after adjustment. Such longitudinal adjustment is desirable 20 because the flow of the ore rock or the like between the rolls tends to groove the roll shells and if means for longitudinal adjustment is provided the relative positions of the shells may be so changed that the grooving can be, to a large extent, worn off by the 25 action of the material that is being crushed. Such adjustment is also desirable to provide for the proper alinement of new shells when they are first put on, inaccuracies or variations 30 in the machining of the taper-bore of the shells causing different shells to take different positions on the shaft.

In the accompanying drawings, Figure 1 is a top plan view of a crushing mechanism 35 provided with my improvements. Fig. 2 is a side elevation of the same. Fig. 3 is a sectional view of the adjusting devices on a relatively large scale and showing also some of the adjacent parts, the section being taken 40 on the line $x-x$ of Fig. 2. Fig. 4 is a face view of the parts shown in Fig. 3. Figs. 5 and 6 are top and face views, respectively, of the adjustment shell. Fig. 7 is a perspective view of one of the parts of the adjusting device. Fig. 8 is a face and edge view of one 45 of the bearing rings.

In the drawings, I have shown enough of a crusher-roll mechanism to indicate how my improvement can be put to use, but a 50 major part of the mechanism will readily be understood by those skilled in the art, so that it will not be necessary to describe it in detail. Suffice it to note that the crusher rolls are indicated by B and C mounted

upon a base A, the roll B being stationary 55 as concerns movement bodily, while the roll C is movable bodily toward and from the companion roll. Such movement is provided for by mounting the roll C in yielding bearings with which springs are combined for the 60 purpose of holding, normally, the movable roll in a predetermined position.

The shaft F of the fixed roll extends longitudinally thereof outward and is mounted in pedestal bearings indicated as entireties 65 at D and D'. The bearing D is formed of the lower pedestal part d and a cap d', these parts being brought into contact on and separable from each other at a plane inclined to the horizontal.

70 The shaft F is provided with a screw-threaded end-part G, preferably formed by shouldering the shaft as shown at f. In the reduced or threaded part G are formed one or more key-ways g extending parallel to 75 the axis. H indicates an adjustable thrust device having a radially arranged flange h, and a threaded tube or sleeve h', fitted to the thread on the part G of the shaft. In this sleeve there is a key-way h² adapted to 80 register with the key-way g in the shaft. After the thrust device has been put into the desired position, it can be fastened therein immovably by means of the key G'. The flange part of the thrust device lies between 85 two abutment walls respectively preventing it from moving either inward or outward along the axis of the shaft, but which permit it to rotate freely. These are provided as follows.

90 K indicates a shell-like structure having a radially arranged wall k and a peripheral wall k'. The latter is threaded internally, as shown at k², to receive the threaded outer edge of the ring or annular plate L. The 95 outer face of plate L is formed with lugs l' adapted to receive a spanner bar or other tool adapted to rotate the ring when it is desired to cause it to move in or out along the axis. These lugs also serve as a locking 100 means for the ring as will presently be explained.

The flange part h of the adjustable thrust device is situated in the space or chamber between the ring L and the inner wall k. 105 M-M are bearing rings or annular washers interposed between the flange h and the wall k on the one side, and the flange and the ad-

justing ring L on the other side. These rings M are grooved at m to provide for the circulation of oil and insure a thorough lubrication of the bearing surfaces.

5 The shell or box-like part K is locked against rotation by means of projections such as the stud-bolts N, secured to the part d of the bearing D, and opposing projections on the part K, these opposing projections in the present instance being radially extending hooks or hooked arms K'. When the shell or box-like part is in place with the hooks K' on the stud bolts and the securing nuts N' are turned home, said shell 10 part is rigidly secured to the pedestal part of the bearing D.

A key-plate O adapted to engage any one of the pairs of lugs l' and drilled at one end to pass over one of the stud-bolts N and be 20 clamped in position by nuts N' constitutes means for effectively locking the plate L, against rotation with respect to the shell K.

By means of sockets at h³, the adjusting nut H can be engaged by a spanner wrench 25 or the like to shift the flange h in or out along the shaft.

When it is desired to draw the shaft and the roll toward the right, the nut and flange at h—h' are turned in such way as to travel 30 inward on the thread of the shaft. As the wall k of the shell part K constitutes a stationary abutment the effect of this movement is to draw the shaft outward. Prior to thus turning the nut and flange h—h' the 35 key or keys G' are removed to free the nut, and after the adjustment has been made, the key or keys are restored. Vice versa, if it be desired to move the shaft in the opposite direction, the nut and flange are rotated in the opposite way, thus causing pressure to be exerted upon the adjusting plate L. As this plate is locked in the shell K which is rigidly secured to the bearing pedestal, it acts as an abutment and the shaft is 45 shifted inward or toward the left.

The hooked arms K' which I employ to secure the shell K in position are an important feature; inasmuch as it permits the roll and its shaft to be raised bodily from 50 its bearings with the adjustment device intact by simply loosening the securing nuts N'.

The shell K is provided on its upper side with a cored extension P having an opening 55 p through which lubricant may be fed to the thrust bearing surfaces of the adjustment device. This opening may be provided with any suitable cover to exclude dust, but in the present instance, I have 60 shown at Q a cover composed of a sheet of flexible material, such as rubber belting with a backing Q' of metal. The cover is secured at its flexible end so that the opposite end may be raised when it is desired to introduce the lubricant.

What I claim is:

1. In crushing rolls, the combination of the machine frame, a roll shaft, an annular bearing shell rigidly secured to the frame and having oppositely facing bearing surfaces, and a thrust-collar adjustably secured on the shaft between the said oppositely facing bearing surfaces, said collar having a part exposed to the exterior of said shell, whereby said collar may be engaged and 70 adjusted inwardly or outwardly with respect to the shaft, substantially as set forth.

2. In crushing rolls, the combination of the machine frame, the roll shaft, the annular bearing shell rigidly secured to the frame and having oppositely facing bearing surfaces, the adjustable thrust-collar secured by screw-threads on said shaft between said oppositely facing surfaces, and means for locking the collar in adjusted position, said 80 collar having a part exposed to the exterior of said shell, whereby the collar may be engaged and turned forward or backward to effect longitudinal adjustment of the shaft, substantially as set forth.

3. In crushing rolls, the combination of the machine frame, the roll shaft, the annular bearing shell rigidly secured to the frame and having oppositely facing bearing surfaces, an adjustable thrust-collar secured by 95 screw-threads on said shaft between said oppositely facing surfaces, and means for locking the collar in adjusted position, said collar having a hub extension projecting to the exterior of the shell and adapted to be 100 engaged and turned forward or backward to effect a longitudinal adjustment of the shaft, substantially as set forth.

4. In crushing rolls, the combination of the machine frame having sectional roll-supporting bearings, a roll shaft in said bearings, the thrust-collar on the shaft, the bearing shell having oppositely facing bearing surfaces to receive the thrust-collar, and releasable fastening means for holding the 105 shell against axial movement, said shell being free when said fastening means is released to be lifted with the roll shaft from its supporting bearings.

5. In crushing rolls, the combination of 115 the machine frame having sectional roll-supporting bearings, the roll shaft in said bearings, the thrust-collar on said shaft adjacent one of the bearings, the bearing shell having oppositely facing bearing surfaces 120 to receive said thrust-collar mounted on an end face of the adjacent bearing, the engaging surfaces of the shell and bearing being constructed to allow free vertical movement of the former, and fastening 125 means to detachably secure the shell rigidly to the bearing, substantially as set forth.

6. In crushing rolls, the combination of the machine frame having sectional roll-supporting bearings, the roll shaft in said 130

bearings, the thrust bearing for said shaft comprising a collar on the shaft, and a bearing shell having oppositely facing bearing surfaces to receive said collar, mounted on the frame, one of the thrust bearing members being axially adjustable to effect the longitudinal adjustment of the roll shaft, and releasable fastening means for securing the shell rigidly to the frame, said shell being free, when the fastening is released, to be lifted with the roll shaft from its supporting bearings.

7. In crushing rolls, the combination of the machine frame, having sectional roll-supporting bearings, the roll shaft in said bearings, the thrust bearing for said shaft adjacent one of the supporting bearings and comprising a collar on the shaft, and a bearing shell having oppositely facing bearing surfaces to receive said collar mounted on an end face of the adjacent supporting bearing, one of the thrust bearing members being axially adjustable to effect the longitudinal adjustment of the roll shaft, and fastening means to detachably secure the shell rigidly to said supporting bearing, the engaging surfaces of the shell and bearing being constructed to allow free vertical movement of the former, substantially as set forth.

8. In crushing rolls, the combination of the machine frame having sectional roll-

supporting bearings, the roll shaft in said bearings, the thrust bearing for said shaft comprising an axially adjustable collar on the shaft, and a bearing shell having oppositely facing bearing surfaces to receive said collar mounted on the frame, and releasable fastening means for holding the shell against axial movement, said shell being free, when the said fastening means is released, to be lifted with the roll shaft from its supporting bearings.

9. In crushing rolls, the combination of the machine frame, having sectional roll-supporting bearings, the roll shaft in said bearings, the thrust-bearing for said shaft adjacent one of the supporting bearings and comprising an axially adjustable collar on the shaft, and a bearing shell having oppositely facing bearing surfaces to receive said collar mounted on an end face of the adjacent supporting bearing, and fastening means to detachably secure the shell rigidly to said supporting bearing, the engaging surfaces of the shell and bearing being constructed to allow free vertical movement of the former, substantially as set forth.

In testimony whereof I affix my signature, in presence of two witnesses.

RICHARD BERNHARD.
